UNITED STATES PATENT OFFICE.

JOHN NEWBERRY REYNOLDS, OF GREENWICH, CONNECTICUT, ASSIGNOR TO WESTERN ELECTRIC COMPANY, INCORPORATED, OF NEW YORK, N. Y., A CORPORATION OF NEW YORK.

TELEPHONE SWITCHING APPARATUS.

1,323,318.

Specification of Letters Patent.

Patented Dec. 2, 1919.

Application filed November 26, 1917. Serial No. 203,942.

To all whom it may concern:

Be it known that I, JOHN NEWBERRY REYNOLDS, a citizen of the United States, residing at Greenwich, in the county of Fairfield and State of Connecticut, have invented certain new and useful Improvements in Telephone Switching Apparatus, of which the following is a full, clear, concise, and exact description.

- 10 This invention relates to switch controlling circuits, and more particularly to circuits for controlling the operation of a line switch of the type used in automatic telephone exchange systems.
- 15 The invention has been shown applied to a crossbar line switch essentially similar in structure to the switch disclosed in applicant's Reissue Patent No. 14,236, issued December 26, 1916.
- 20 The object of this invention is the provision of a simple, reliable and improved circuit arrangement for operating such switch.

In accordance with this object each trunk bar is provided with electromagnetic operating means individual thereto to preselect it for use, and when a trunk is preselected the electromagnetic operating means of another trunk bar is allotted for subsequent 30 operation.

Also in accordance with this object means are provided for preventing the operation of the switching means for extending a calling line to a called line during the time required for the setting of a trunk bar.

In accordance with this object, means are also provided to prevent the operation of a line bar when the telephone line associated therewith is a called line.

40 Other features will appear from the following description and claims.

For a more complete description of the device reference is now made to the drawing, which shows a perspective view of the 45 switch with parts broken away, and a circuit arrangement for operating the device.

Referring now to the drawing, the line bars 1 are pivotally mounted in the sides of a frame (not shown). Each of these line bars is provided at one end with a right angular extension 2, through which projects a pivot pin 3. The other end of each bar also has an angular extension 4 from which projects a pivot pin 5 received by an opening in the frame. Secured to the bars 1,

but insulated therefrom and from each other, are the three conducting strips 6, 7 and 8. These strips are provided with a plurality of integral spring contacts 9, 10 and 11, respectively. Each line bar carries 60 as many of these sets of contacts as there are trunk bars in the structure.

Pivottally mounted between the top and bottom of the frame is a plurality of trunk bars 80, one being provided for each trunk 65 or connecting circuit. These bars are pivotally mounted by means of pins 14 and 15; which extend through openings in the right-angular extensions 12 and 13 at each end of the trunk bars. Secured to the bars 80, 70 but insulated therefrom and from each other, are the conducting strips 16, 17 and 18. These strips are provided with a plurality of integral spring contacts 19, 20 and 21, respectively; one set being provided for 75 each line bar in the switch or for each subscriber's line in the group. These sets of springs project from the trunk and line bars at points adjacent to the points of intersection of such bars. Projecting from the 80 extension 13 of each trunk bar is a catch lever 22, normally retained in a retracted position by a spring 23. Pivottally mounted on the frame is a plurality of catches 24, one for each trunk bar, each catch being arranged to engage and hold a catch lever 22 when its associated trunk bar is rotated in a clockwise direction (as viewed in the drawing) by the armature 66 of a magnet 65.

A shoulder 52, provided on each trunk 90 bar 80, is arranged to engage an insulating pin 53 fastened to a spring 54 so that, upon clockwise rotation of the bar to its set or selected position, the pin 53 opens the normally closed springs 54 and 55 and closes 95 the normally open springs 55, 58 and 54, 57.

A common latch bar 60 is slidably mounted in the supports 61. This bar 60 has a plurality of lugs 62, one for each trunk bar, and they are so arranged that, when a trunk bar is displaced, the catch lever 22 associated with the displaced trunk bar engages a lug 62, and moves the bar to the left. A pin 63 of insulating material is fastened to the latch bar 60 and is arranged to keep the 100 normally closed contact 64 open whenever any one of the trunk bars 80 is displaced.

A shaft 27 is rotatably mounted in the frame in any suitable manner, and rigidly fastened to the shaft are the ratchet wheel 110

28 and contact wipers 32 and 33. A pawl 29, carried by the armature 30 of an electromagnet 31, engages the teeth of the ratchet wheel 28 to rotate the shaft 27 and the 5 wipers secured thereto. Wiper 33 engages a set of contacts 94 in which terminate the circuits leading to the operating magnets 65 of the trunk bars. Wiper 32 engages the test contacts 93 for testing the trunk bars 10 to preselect an idle one in a manner herein-after described.

Mounted on the frame is a plurality of operating magnets 40. Each magnet is provided with two windings, a low resistance winding 41' and a high resistance winding 41. Each magnet 40 is also provided with a pivoted armature 42, having a right-angular projection 43, ending in a cam member 44. Projecting upward from 15 each line bar and in a position for engagement by its respective cam member 44, is a pin 45 by means of which the line bar may be rotated upon the attraction of the armature 42. Upon further attraction of the 20 armature 42 a shoulder 46 on the member 43 is arranged to engage the pin 5 in such a manner as to force the line bar to the left, as viewed in the drawing. Springs 47, 48 are provided for returning the line bar to its 25 normal position. Sets of contacts 49 and 50 are arranged to be operated by a pivoted armature 51 of the magnet 40. This magnet is so constructed that, when winding 41' is energized armatures 42 and 51 are attracted, and when winding 41 is energized, armature 51 will be attracted and armature 42 will not be, but if the armatures are already attracted, the current through winding 41 will be sufficient to maintain the armatures attracted when the circuit through winding 41' is opened.

It is believed that the invention will now be better understood by describing the operation of the switch.

45 Upon the subscriber at substation A removing his receiver from the hook, a circuit will be completed from battery, contact 49, left-hand winding of relay 70, conductor 71, telephone apparatus at substation A, conductor 72, right-hand winding of relay 70, contact 50 to ground. Relay 70 is thereupon energized and completes, through its armature, a circuit from battery, armature and back contact of relay 75, conductor 74, low 50 resistance winding 41' of magnet 40, conductor 73, armature and front contact of relay 70 to ground. Armatures 42 and 51 are thereupon attracted, armature 51 opening the contacts 49 and 50 and causing the de- 55 energization of slow relay 70, while armature 42, through the engagement of cam 44 with pin 45, causes the line bar 1 to be rotated. The rotation of this line bar causes the contact terminals 9, 10 and 11 to move 60 65 downwardly, and places one set of the terminals

in operative relation to contacts 19, 20 and 21, respectively, of the preselected trunk bar 80. Upon further attraction of the armature 42, the engagement of shoulder 46 with pin 5 forces the bar 1 to the left, 70 bringing the contacts of the line bar into engagement with the trunk terminals, and also moving the unengaged terminals of the line bar to a position wherein they will not be engaged by the terminals of another 75 trunk bar. Upon engagement of the line terminals 9 and 10 with the trunk terminals 20 and 21, a circuit is completed for relay 76 from grounded battery, relay 76, conductor 77, conducting strip 18, terminals 80 21 and 9, conducting strip 6, conductor 71, telephone apparatus at substation A, conductor 72, conducting strip 7, terminals 10 and 20, conducting strip 17, conductor 79 to ground. Relay 76 thereupon becomes 85 energized and places ground on conductor 81 to cause the test terminal 93 to test busy and to place ground upon the test strip 16 when the trunk bar is released. Upon engagement of terminals 11 and 19, a circuit 90 is completed for the high resistance winding 41 of magnet 40 in series with trip magnet 26, from grounded battery, winding 41 of magnet 40, conducting strip 8, terminals 11 and 19, conducting strip 16, conductor 95 84, springs 55, 58, conductor 85, magnet 26 to ground. Magnet 26 thereupon becomes energized and by attracting its armature 24 releases the trunk bar, which is returned to its normal position by spring 23. Trunk 100 bar 80, by returning to its normal position, opens springs 55, 58 and closes springs 55, 54, thereby closing a holding circuit for magnet 40 through the high resistance winding 41 to ground at the armature and 105 front contact of relay 76. Magnet 40 thereby maintains the line bar 1 in engagement with the trunk bar 80.

When the trunk bar 80 returns to its normal position, terminals of the set which are 110 in engagement with the line terminals remain in contact therewith, due to the flexibility of said terminals. The other sets of terminals, carried by the trunk bar, are rotated in an anti-clockwise direction, as 115 viewed in the drawing, to place them in a position where they will not be engaged by the terminals carried by the bar of the next calling line. The trunk bar, in returning to its normal position, also allows the latch 120 bar 60 to be returned to its normal position by spring 87, and close the contacts 64 to complete a circuit for the pilot relay 75. Relay 75, by attracting its armature, disconnects battery from conductor 74 common 125 to all of the windings 41' of the line bar operating magnets, thereby preventing the operation of another line bar until a trunk bar has been displaced. A circuit is closed at the same time for the magnet 65 of the 130

trunk bar next to be selected, through wiper 33, which is now in engagement with the contact 94 leading to such magnet, the circuit for this magnet being from grounded 5 battery, magnet 65, conductor 87, contact 94, wiper 33, conductor 88, left-hand armature and back contact of relay 89, conductor 90, contact 64 to ground. The magnet 65, by attracting its armature 66, causes its 10 associated trunk bar to assume a set position ready for engagement by the line terminals on the bar of the next line to call. This attraction of armature 66 also closes contacts 86, which completes a circuit for 15 test relay 89 from grounded battery, relay 89, conductor 91, contacts 86 to ground. Relay 89 closes at its right-hand armature and front contact a circuit for the stepping magnet 31 from grounded battery, right-hand 20 armature and front contact of relay 89, magnet 31, armature 30 to ground. The attraction of armature 30 of the magnet 31 causes, through the pawl 29, the rotation of the shaft 27 to successively move the wipers 32 25 and 33 into engagement with the contacts 93 and 94, respectively. As long as wiper 32 engages test contacts 93 of busy trunk lines upon which ground is impressed at the armature and front contact of relay 76 or 30 through contacts 57 and 54 if the trunk bar is set, the test relay will be energized and the stepping circuit will be completed, the shaft being rotated by the successive energization and deenergization of the magnet 31, 35 due to the breaking of its circuit by the attraction of its armature 30. When, however, the wiper 32 reaches a test contact 93 of an idle trunk, no ground will be thereon and the test relay 89 will become deenergized. The retraction of its right-hand 40 armature will open the stepping circuit for magnet 31, thus stopping the shaft 27 with the wiper 33 in engagement with the contact 94 to which the operating magnet 65 of the 45 idle trunk is connected. Wiper 33 now completes the circuit of this magnet 65 of the idle trunk to the contacts 64 so that, upon the longitudinal movement of the latch bar 60 when the set trunk bar is seized, the 50 magnet 65 of this idle trunk will become energized and position the trunk bar of this idle trunk in a position for the reception of the next call.

Upon the calling subscriber hanging up 55 his receiver at the termination of the conversation, the circuit for relay 76 is interrupted and the retraction of its armature opens the holding circuit for the magnet 40. The deenergization of the magnet 40 causes 60 the retraction of its armature 42, thus releasing the line bar which is thereupon returned to normal by the springs 47 and 48, carrying therewith the terminals 9, 10 and 11, previously in engagement with the trunk 65 terminals 21, 20 and 19.

When subscriber A is a called party and the connector brushes (not shown) engage terminals of the conductors 95, 96 and 97, ground will be connected to the conductor 97 in a well-known manner, causing the 70 energization of the winding 41 of magnet 40. As previously described, the current through this winding alone is insufficient to attract armature 42, but does attract armature 51, which opens contacts 49 and 50 so 75 that, when the subscriber A removes his receiver in answering the call, relay 70 remains deenergized as its circuit is open at contacts 49 and 50, and, therefore, winding 41' of the magnet 40 does not become energized to move the line bar into engagement with a displaced trunk bar.

What is claimed is:

1. In combination, two groups of lines, a plurality of switching devices for connecting a line of one group to an idle line of the other group, electromagnets individual to each of said switching devices for pre-selecting it for operation, and means operated by the operation of a preselected 85 switching device for energizing one of said electromagnets to preselect the switching device associated therewith and for selecting another electromagnet for successive 90 operation.

2. In combination, incoming and outgoing lines, a switching device comprising two sets of rotatable shafts, the shafts of one set being at an angle to those of the other, contact terminals of said incoming and outgoing lines carried by the shafts of said sets respectively, means whereby the rotation of a shaft of each set in a definite order will cause the engagement of their respective contacts, electromagnetic operating means individual to each shaft of one set, and means for operating one of said electromagnetic operating means to normally position one of said shafts of one set to engage terminals on any shaft of the other set and to preselect another one of the electromagnetic operating means for successive 100 energization.

3. In a switch, a plurality of trunk bars, contacts on said trunk bars, a plurality of line bars, contacts on said line bars arranged to engage the contacts on said trunk bars, means for displacing each of said trunk bars into a position to have its contacts engaged by the contacts on said line bars, means for displacing said line bars, and means operated when the contacts on the displaced trunk bars are seized by the contacts on the line bar for preventing the operation of the last-mentioned displacing 115 means until another trunk bar is displaced.

In witness whereof, I hereunto subscribe my name this 22nd day of November A. D., 1917.

JOHN NEWBERRY REYNOLDS,
